United States Patent Office.

BENJAMIN R. COLE, OF BUFFALO, NEW YORK.

Letters Patent No. 90,502, dated May 25, 1869.

IMPROVEMENT IN WATER-CLOSETS.

The Schedule referred to in these Letters Patent and making part of the same.

To all whom it may concern:

Be it known that I, BENJAMIN R. COLE, of the city of Buffalo, in the county of Erie, and State of New York, have invented a certain new and useful Improvement in Self-Acting Water-Closets; and I do hereby declare that the following is a full and exact description thereof, reference being had to the accompanying drawings, making part of this specification.

My improvement is designed to be applied to that class of pan water-closets in which the pan and water-valve are operated by means of a pull and side lever, for the purpose of rendering the same self-acting, the pull being retained or not, as preferred.

The invention consists—

First in the combination and arrangement of a lever and push-rod with said side lever, so that the latter will be operated by pressure on the seat, instead of by the pull, as in the ordinary manner.

Second, in constructing the said auxiliary lever with fulcrum-notches and an adjustable segment, by which the relative position of the lever, as to its fulcrum, can be changed to adapt it to the other parts of the apparatus, as hereinafter set forth.

In the drawings—

Figure I is a front elevation of a water-closet provided with my improvement, the front side of the case being removed to exhibit the parts.

Figure II is a similar side view.

Figure III is a longitudinal section of a portion of my auxiliary lever, showing its construction and connection with the fulcrum.

Like letters of reference designate like parts in each of the figures.

A is the basin of a water-closet.

B, the pan, shown in dotted lines, underneath the basin.

C, the side lever, pivoted at d, and operated by the pull-rod e at the opposite end.

F is the slotted crank-arm, connected to the lever by a bolt fitting in the slot, by which the pan is operated.

g is a crank or arm for operating the water-valve, which is not shown in the drawings.

H is a link or slotted bar for connecting the pull with the lever, for adjusting the length of the pull.

The foregoing parts, which are old and well known, may be constructed in any common or suitable manner.

I is my auxiliary lever, arranged in front, beneath the side lever.

J is the fulcrum thereof.

k is a push-rod, connecting the front edge of the hinged seat L with the short arm of the lever, and

M is a weighted bar connecting the opposite end of the lever with the link H.

The length of the push-rod may be adjusted by means of a swivel-nut, l', as shown.

The link H enables the length of the connection between the two levers to be readily adjusted by means of the set-bolt m, which may be fixed at any point in the slot in said connection.

The end of the long arm of lever I is slotted and provided with adjusting-holes, for uniting with the connection M, at different points, as occasion may require.

The weight of the connection M should be sufficient to cause a preponderance at that end of the levers, so as to maintain the parts in their normal position when the closet is not in use.

The fulcrum J consists of a standard, which passes up through a slot, n, in the lever I, the edges of the latter, on each side of the slot, on the under side, being formed with a series of transverse notches, s s, in any of which are designed to fit the angular shoulders o o, formed on each side of the standard, and constituting the fulcrum.

P is a slotted segment, resting on the upper side of this lever, with tongues or tenons q q', extending downward in the slot of the lever; the tenon, q', being provided with a pin, which passes through its end, and in any one of the notches s, in which, it may be adjusted, which serves as a key to secure it in place.

The standard J, reduced in size, passes up through the slot in the segment, where it is provided with a nut, r, which screws down loosely against the segment, and secures the lever in place on the fulcrum.

The fulcrum J being bolted to the floor at a suitable point, the lever is adjusted with any of the notches s resting thereon, and the segment arranged so that the fulcrum-points will form the centre thereof.

This adjustment will permit the free movement of the lever, while the connection between the lever and fulcrum is maintained secure against displacement.

The facility of adjustment which characterizes my improvement, enables it to be readily applied to water-closets that are in use, at but a small expense.

The advantages of a self-acting water-closet, over one operated by a pull, are well understood; the pull of the latter frequently receiving no attention, either from the carelessness, indifference, or ignorance of persons using the closet, which is especially the case with water-closets in hotels and other places, designed for public use.

By the employment of my improvement, no such results can ensue, the proper operation of the parts at all times being insured.

What I claim as my invention, and desire to secure by Letters Patent, is—

1. The combination and arrangement, with the side lever C, of the auxiliary lever I, weighted connection M, and push-rod k, operated by seat L, substantially as set forth.

2. The segment P, fulcrum-standard J, and lever I, provided with slot n and notches s, for rendering the lever adjustable, and securing it in place, all arranged and combined as set forth.

B. R. COLE.
